UNITED STATES PATENT OFFICE.

ADOLPH LANGSNER, OF CHICAGO, ILLINOIS, ASSIGNOR TO EUGENE DIETZGEN CO.,
OF CHICAGO, ILLINOIS, A CORPORATION OF DELAWARE.

TAPE REEL.

Application filed June 4, 1925. Serial No. 34,770.

My invention relates to tape reels, especially of that type, in which the drum is rotated by means of a handle hinged to the front of the drum and capable of occupying both an extended and folded position radially. When in folded position the crank is usually in close contact with the front of the drum, and a push pin is slidably mounted at the center of the drum for pushing the crank outward for releasing it from its latch. One of the objects of my invention is to simplify the formation of the pin and the construction at the center of the drum. Another object is to simplify the mechanism for attaching the inner end of the tape to the drum.

I accomplish my objects by the mechanism illustrated in the accompanying drawings, in which—

Figure 1 is a front assembly view of the article, certain portions being broken away in order that the view may be drawn on a large scale.

Figure 2 is a sectional view of the parts shown in Figure 1, the planes of section being indicated by the broken line 2—2 Figure 1.

Figure 3 is a top view of the drum showing the manner of attaching the tape to it.

Figure 4 is a perspective view looking toward the inside of the drum.

Figure 5 is a perspective view of the anchoring head of the tape, and

Figure 6 is a perspective view of the sleeve which supports the rear end of the hub of the drum.

Like numerals denote like parts throughout the several views.

In the form chosen to illustrate the invention the casing is formed in two parts 10 and 12. These have interfitting flanges 14 and 16 respectively by which they are held together in spaced relation as illustrated in Figure 2. The part 10 is at the front and has an opening in the center for rotatably supporting the cylindrical portion 18 of the tape drum. This drum is formed preferably of a piece of drawn sheet metal with a peripheral beading 20 at the front and having the front closed by a head or front pawl 22.

A crank 24 is hinged by a pin 26 to the front 22 of the drum in the usual manner. It is capable of occupying an extended position as shown in full lines in Figures 1, 2,

3 and 4, and also a folded position as shown in dotted lines Figure 2. In this latter position it is in contact with the front of the drum and its handle 28 is engaged by a latch 30 which yieldingly locks the crank in this position. The latch is in the form of a tongue struck from the cylindrical portion 18 of the drum and the handle passes into it and through an opening 32 in the front of the drum. The drum has a central opening 36 at the front for supporting the front extension 38 of a drum 34. This extension is peened over at the margin, and by this means is rigidly secured to the drum.

The rear end of the hub is supported by a sleeve 40 shown in section in Figure 2 and in perspective in Figure 6. The sleeve surrounds the hub and is crimped to it in order to securely hold the hub and the sleeve together as one piece. At its rear end the sleeve projects out through an opening 42 in the rear wall of the casing, and has a flange 44 which lies adjacent to the outer surface of the rear wall of the casing. The sleeve fits loosely enough in said rear wall to enable it to rotate freely.

The hub is centrally chambered to receive a push pin for releasing the crank from latch 30. This pin is formed in three sections. The body section 46 is at the middle. A reduced section 48 projects out through an opening 50 in the front of the hub and another portion 52 projects out through the back of the hub. The front of the hub forms a stop for limiting the forward movement of the pin. At the rear the hub has a flange 54 which is pressed inward sufficiently to engage the shoulder 56 at the junction of the body portion with the reduced portion 52 of the pin. This flange 54 is bendable in the sense that the flange may be pressed or swaged inward as shown. This greatly simplifies the construction for it avoids the need of any nuts or similar stops which would add to the complexity of the construction.

The tape 60 has an anchoring head 62 which is wider than the normal width of the tape and is adapted to enter a slot 64 arranged circumferentially in the cylindrical portion 18 of the drum. The slot is somewhat longer than the width of the head, and the result is that the parts may be assembled by inserting the head in the slot lengthwise and then rotating it 90 degrees, whereupon

the tape will be anchored in the manner illustrated in Figure 3.

Operation: When the device is in use the crank 24 will occupy the extended position shown in Figure 2. Under these conditions when the crank is rotated it will rotate the drum, which makes a running fit with the front wall 10 of the casing while the cylindrical portion of sleeve 40 makes a running fit with the rear wall 12 of the casing.

When the device is not in use the crank will be swung to folded position shown in dotted lines in Figure 2, in which position the latch 30 will take hold and prevent the crank from swinging away from the folded position. When it is desired to use the device, the operator presses upon the rear end of the push pin which in turn pushes outward on the crank and releases it so that the operator may readily swing it to the acting or extended position shown in full lines.

It will be observed that the parts are few in number and are very simply and durably constructed. The connection of the hub to the drum is especially simple, the forward end of the hub being merely swaged or peened over the drum. This dispenses with any threading operation and with the use of lock nuts or similar devices. The construction at the rear of the hub is also very simple for the flange 54 of the hub is not pressed inward until after the body of the pin has been inserted, after which the pin is securely retained and no threading operation is required nor any lock nuts or similar devices. The support for the rear end of the drum is also simple for here again threading is dispensed with and the sleeve is merely crimped or pressed onto the hub. The parts may be assembled from the back of the casing, after which the front end of the hub is peened over at the rim and the parts will be securely held.

It will be noted that the means for attaching the tape to the drum are also simple and dispense with rivets, screws and like elements. Furthermore the tape is readily detachable at all times.

Having thus described my invention what I claim as new and desire to secure by Letters Patent is:

1. A tape reel having a casing for the tape, a drum rotatably mounted within the casing for supporting the tape, a crank pivoted to the drum for rotating it, the crank being hinged to the front of the drum whereby it may occupy either an extended or a folded position, radially, a hub arranged

axially at the center of the drum, a push pin 60 slidably mounted within the hub in an axial direction for pushing the crank outward from its folded position, and means on the hub for limiting the forward movement of the pin, the pin having a shoulder and the hub having a bendable flange at the rear end 65 pressed radially inward for engaging the shoulder to thus retain the pin within the hub.

2. A tape reel having a casing for the tape, a drum rotatably mounted within the 70 casing for supporting the tape, means for rotating the drum, a hub arranged axially at the center of the drum and attached to the front of it, and a sleeve secured to the rear of the hub for supporting it, the rear wall of 75 the casing having an opening and said sleeve being journaled in said opening and having a flange engaging the outer surface of the rear wall for preventing endwise movement of the hub in a forward direction. 80

3. A tape reel having a casing, a drum rotatably mounted within the casing for supporting the tape, means for rotating the drum, a hub arranged axially at the center of the drum, the forward end of the hub 85 passing through an opening in the front of the drum and being peened over the margin of said opening, and a sleeve crimped upon the hub to thereby become fastened to it, and the rear end of the sleeve being journaled 90 in an opening in the rear wall of the casing and having a flange making running contact with the outer surface of the rear wall of the casing.

4. A tape reel having a casing, a rotatable 95 drum journaled within the casing for supporting the tape, a crank hinged to the front of the drum and capable of occupying either an extended or a folded position in contact with the front of the drum, a hub secured at 100 its front end to the drum and having means at the rear end whereby it is rotatably supported within the casing, the hub being chambered and having reduced openings at each end, and a push pin having a body slideable axially within the chamber of the hub, one reduced end of the pin projecting forward toward the crank for pressing it outward, and the other reduced end projecting rearward out through the hub, the rear end 110 of the hub having a thin flange pressed radially inward to confine the body of the pin within the hub.

In witness whereof, I have hereunto subscribed my name.

ADOLPH LANGSNER.
